UNITED STATES PATENT OFFICE

150,461

DESIGN FOR A CHAISE LONGUE

Alice Roth, Troy, Ohio, assignor to The Troy Sun-shade Company, Troy, Ohio, a corporation of Ohio

Application December 26, 1946, Serial No. 135,776

Term of patent 7 years

(Cl. D15—11)

To all whom it may concern:

Be it known that I, Alice Roth, a citizen of the United States and a resident of the city of Troy, county of Miami, and State of Ohio, have invented a new, original, and ornamental Design for a Chaise Longue, of which the following is the specification, reference being had to the accompanying drawings, forming part thereof, wherein:

Figure 1 is a perspective view of a chaise longue according to my design;

I claim:

The ornamental design for a chaise longue, substantially as shown.

ALICE ROTH.
